(57) **CLAIM**

The ornamental design for a bay window curtain support, as shown and described.

DESCRIPTION

FIG. 1 is a perspective environmental view from the front and top of a bay window curtain support showing my new design.

FIG. 2 is front elevation view thereof.

FIG. 3 is rear elevation view thereof.

FIG. 4 is left side elevation view thereof.

FIG. 5 is right side elevation view thereof.

FIG. 6 is top plan view thereof; and,

FIG. 7 is bottom plan view thereof.

The broken line showing of a bay window and portions of the design and support structure is included for the purpose of illustrating environmental structure and forms no part of the claimed design.

1 Claim, 6 Drawing Sheets
